UNITED STATES PATENT OFFICE.

JOHN CHARLES HOWELL, OF LONDON, ENGLAND.

HOIST, WINDING-GEAR, &c.

SPECIFICATION forming part of Letters Patent No. 660,685, dated October 30, 1900.

Application filed September 26, 1899. Serial No. 731,736. (No model.)

To all whom it may concern:-

Be it known that I, JOHN CHARLES HOWELL, a subject of Her Majesty the Queen of Great Britain, residing at London, England, have 5 invented a certain new and useful Improvement in Hoists, Winding-Gear, and the Like, of which the following is a specification.

This invention relates to a certain improvement in hoists, winding-gear, and the like, 10 the object of the invention being to provide a compact and handy hoist or the like capable of being operated from an electric motor through a reducing-gear and so arranged that the hoist or the like may be self-sustaining as 15 to its load and that the motor may be capable of being started without any load, which can be afterward gradually put on.

The invention is illustrated in one form in the accompanying drawings, which represent, 20 in—

Figure 1, an elevation, partly in section, of the motor, reduction-gear, braking and driving rings, and hoisting-drum, and in Fig. 2 a detail sectional view of the lower portion of 25 the controlling-lever, &c.

In the drawings, *a* represents an electric motor; *b*, the reduction-gear; *c*, the braking and driving rings, and *d* the hoisting-drum.

The reduction-gear *b* is of the class described in Letters Patent of the United States granted to Thomas Humpage on the 11th of July, 1899, under No. 628,469, and consists of a bevel gear-wheel *B*, carried by the fast-running shaft *a'* of the motor, a bevel gear-wheel 30 *D*, loosely mounted on a stud at an angle to said wheel *B* and gearing therewith, and a stationary gear *K*, secured to the cover-plate *b'* of the gear-casing *b*. The gear *D* carries a gear *E*, fixed to it or forming part of 35 same and both run freely on the stud, which is in turn carried by a spindle *b*, which can turn freely in the fast-running shaft *a'* and in the slow-running shaft *b*, which carries a bevel gear-wheel *M*, engaging with the bevel- 40 gear *E*. The wheels *E* and *D* are duplicated, as shown, to secure a better balance for the gear. The shaft *b* carries a driving disk or ring *c'*, between which and a similarly-shaped 45 braking disk or ring *c* is situated a toggle-arm *c*, having two friction holding-faces *c*, one being adapted to engage with the interior surface of the driving-disk *c'* and the

other with the interior surface of the braking-disk *c* alternately. The toggles *c*, of which there are preferably a set arranged on opposite sides of the shaft *d* of the drum *d*, are pivotally attached to a boss *d* on the end of said shaft and are provided with a projection or rounded nose *c*, which separates the two disks and the rounded surfaces of which work against the edges of the disks when the toggles are rocked, the object of the device being to support and steady the toggles at their outer ends. The disk *c* is fixed in some suitable way, as by bolting, to a lug *c* on one 65 of the bearing-pillars.

The shaft *d* is supported in bearings *e* and is capable of longitudinal movement therein. The drum *d* is secured on such shaft, or the shaft may slide in the drum, so long as 70 it is capable of turning it, and said shaft is provided with a collar *d*, which is partly embraced by the operating-lever *f*. This lever is bolted to a disk *g*, which is provided with cross-slots *g'*, by which the lever may be set 75 in different positions according to the position in which the hoist is fixed. The lever may be operated by a rope or chain, so that it may be worked from a distance. The disk *g* is provided with a stud or shaft *g*, journaled 80 in a bearing-block *g*, and to the end of the shaft an arm *h* is rigidly connected. The arm *h* projects into a hollow base-plate *i*, and to it is connected one end of a spring *k*, the other end of which is secured to a hook *l*, bolted to 85 a block *m*, secured to the base or otherwise attached to some fixed point. The pull of this spring forces outwardly the end of the lever *f*, embracing the collar *d* of the drum, thus moving the drum to the right, with the 90 result that the faces *c* of the toggles *c* are pressed against the inside of the brake disk or ring *c* and the drum is held, this being the normal position of the parts, so that a load carried by the drum may be sustained at any 95 point, which is of advantage in the event of a breakage of any part of the driving mechanism.

The driving mechanism, which includes the disk or ring *c'*, may be kept constantly running, if desired, and to put the hoist in action the lever is pushed over, so as to remove the face *c* from disk *c* and put the face *c* gradually into contact with the rotating disk or

ring c' . To lower the load, the same operation is performed, but the lever is only put over sufficiently far to partly release the face c' of the toggle from the braking-disk, by 5 which means the load can be gradually lowered, the operator keeping the same well under control by increasing the braking action when desired.

What I claim is—

10 In a hoist the combination with a reduction-gear and a drum of a part driven through the gear a fixed part separated from the first a shaft on which the drum is supported means

for shifting said shaft longitudinally toggles carried by said shaft and friction-faces on 15 said toggles adapted to be brought into contact alternately with the driven part and the fixed part substantially as described.

In testimony whereof I have hereunto set my hand in the presence of two subscribing 20 witnesses.

JOHN CHARLES HOWELL.
